CLAIM

The ornamental design for a clothes rack, as shown and described.

DESCRIPTION

FIG. 1 is a perspective view of a clothes rack showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 2; and,

FIG. 11 is a partial enlarged view of FIG. 2.

The broken lines in the figures are for the purposes of illustrating portions of the clothes rack, which form no part of the claimed design.
